WILLIAM C. LANG, OF CLEVELAND, OHIO.

SAND-COMPRESSING MEANS FOR MAKING MOLDS.

1,137,638.

Specification of Letters Patent. Patented Apr. 27, 1915.

Application filed April 20, 1914. Serial No. 833,097.

To all whom it may concern:

Be it known that I, WILLIAM C. LANG, a citizen of the United States of America, residing at Cleveland, in the county of Cuyahoga and State of Ohio, have invented 5 certain new and useful Improvements in Sand-Compressing Means for Making Molds; and I hereby declare the following to be a full, clear, and exact description of the invention, such as will enable others skilled in the art to which it pertains to make and use the same.

This invention relates to improvements in sand-compressing means for making molds, and pertains more especially to means whereby during the simultaneous compression of the body of molding sand supplied to each of the vertical compartments into which the upper flask-section of 20 a mold is divided and the body of sand supplied to the lower flask-section of said mold against opposite faces respectively of a double-faced pattern-plate the extent of compression of the sand-body in each of the 25 aforesaid compartments shall be substantially equal to the extent of compression of the sand-body in the lower flask-section.

The primary object of this invention is therefore to attain equality in the compression of said sand-bodies in compressing the 30 molding sand supplied to said flask-sections during a relative readjustment of a mold-bottom embraced by the lower end of the lower flask-section, the pattern-plate interposed between the two flask-sections, and 35 the means employed in exerting pressure on the molding sand in the compartments of the upper flask-section.

Another object is to reduce to a minimum 40 the friction between each upright wall of each sand-receiving compartment of the upper flask-section and the means employed in covering and compressing the body of molding sand supplied to said compartment.

With these objects in view, this invention 45 consists in certain features of construction, and combinations and relative arrangement of parts, hereinafter described, pointed out in the claims, and illustrated in the accompanying drawings.

In said drawings, Figure 1 is a vertical section showing a double-faced pattern-plate interposed between the upper flask-section and the lower flask-section and illustrating the depressibility of said flask-sec- 50 55 60 65 70 75 80 85 90 95 100 105 110

tions and the pattern-plate independently of the mold-bottom and also illustrating the application of improved means for compressing the sand supplied to the compartments of the upper flask-section. Fig. 2 is a horizontal section on line 2-2, Fig. 1. Fig. 3 is a vertical section on line 3-3, Fig. 1.

Referring to said drawings, A indicates the vertically arranged lower flask-section which is shown supplied with a body of molding sand *a*, and a horizontally arranged mold-bottom *B* forms the base for the sand-body *a* and extends into the lower end of said flask-section to render said flask-section depressible independently of said mold-bottom, but I would here remark that said sand-body is somewhat compressed upon supplying it to said flask-section to create enough friction between the said sand-body and said flask-section to prevent descent of said flask-section by gravity. The lower flask-section is therefore filled, between the mold-bottom and the pattern-plate with a somewhat compressed body of molding sand. The mold-bottom *B* is supported in any approved manner, as, for instance, by a floor or table, the top surface whereof is represented by the horizontal line *b*.

A double-faced pattern-plate *C* covers the body of molding sand and rests on the lower flask-section *A* and lies in a substantially horizontal position.

The mold-bottom *B* is supported in any approved manner and thick enough to extend downwardly from the sand-body *a* in the lower flask-section *A* far enough below the lower extremity or externally of said flask-section to permit the descent of said flask-section independently of the mold-bottom far enough to effect the requisite relative readjustment of the pattern-plate and the mold-bottom to sufficiently reduce the distance between the mold-bottom and the pattern-plate and thereby compress said sand-body the extent required.

D indicates the upper flask-section which is mounted on the pattern-plate *C* and arranged in line vertically with the lower flask-section *A*. The upper flask-section is divided internally into substantially corresponding vertically arranged compartments 5 each of which is supplied with a body of molding sand *d*, and the partition 6 between adjacent compartments is conse-

quently arranged vertically. The pattern-plate C has its upper face spaced from the bottom edges of the partitions 6 so that in supplying the compartments 5 with molding sand upon mounting the upper flask-section on the pattern-plate molding sand will run to and cover said edges of the partitions and form an unbroken or continuous layer of sand on the pattern-plate.

Resting upon the body of molding sand within each compartment 5 is a comparatively thin horizontally arranged metal plate e which is large enough in dimensions to cover said body of molding sand and consequently extends into close proximity to the upright walls of said compartment. Each plate e is carried by a wooden slab E to which said plate is secured preferably removably by screws 7, as shown in Fig. 1.

Each slab E is smaller in dimensions horizontally than and arranged centrally relative to the plate e carried by the slab. It will be observed therefore that each slab E is narrower and shorter than the connected plate e and has its edges spaced inwardly from the edges of the plate. All the slabs e are tied together by a board G which is arranged at and extends across the upper sides of said slabs and has the slabs secured thereto in any approved manner, and said board is provided at its upper side with cleats 8 arranged parallel with the slabs and suitably attached to and reinforcing said board.

The arrangement of the parts is such that when the plates e have entered the compartments 5 from above a suitable distance during the application of the board G upon supplying said compartments with molding sand to a suitable height, the board is spaced from the top edges of the partitions 6, and hence it will be observed that said board and connected plate-bearing slabs are capable of being depressed independently of the upper flask-section. The partitions 6 are of course necessary to support the molding sand compressed within the upper flask-section upon the completion of the cope formed by said flask-section and compressed sand therein.

It is obvious that a depression of the board G results in the descent of all of the sand-compressing plates e and in the simultaneous compression of the sand in the different compartments 5 of the upper flask-section; that the compression of the sand in the upper flask-section against the pattern-plate by the plates e creates enough friction between the sand-body d in each compartment 5 and the upright walls of the said compartment to depress or lower the upper flask-section, and of course a depression or lowering of the upper flask-section and a compression of the molding sand in said flask-section against the pattern-plate results in the depression or lowering of the

pattern-plate and the lower flask-section independently of the mold-bottom so that the sand-body in the lower flask-section is compressed during the compression of the sand in the upper flask-section.

I would here remark that if the sand-compressing plates e were not employed and in lieu thereof the slabs E were as large in dimensions as said plates and employed as sand-compressing bodies the friction between the edges of the slabs and the upright walls of the compartments in the upper flask-section, owing to the comparatively great thickness of the slabs, would be so great that said slabs would not lower far enough independently of the upper flask-section during the compression of the sand-bodies in both flask-sections to have the extent of the compression of the sand within the upper flask-section as great as the compression of the sand-body within the lower flask-section. By my improved construction and relative arrangement of the parts and employing thin plates as the sand-compressing bodies for the upper flask-section the friction between each of said sand-compressing bodies and said flask-section is reduced to a minimum and friction between each slab and said flask-section is entirely obviated so that the sand-compressing plates will during the depression of the board G in compressing the sand in said flask-section move far enough independently of said flask-section to effect an adequate compression of the sand-body in each compartment of said flask-section.

What I claim is:—

1. Sand-compressing means for making molds, said means comprising horizontally arranged plates adapted to cover the molding sand in different compartments respectively of a flask-section and to extend into close proximity to the upright walls of the respective compartments; slabs arranged over and carrying the different plates respectively and being each smaller in dimensions horizontally than the connected plate, and a board extending across the upper sides of and secured to said slabs, which board is provided at its upper side with reinforcing cleats arranged parallel with the slabs.

2. The combination, with a substantially horizontally arranged pattern-plate, and a flask-section arranged on the pattern-plate and having vertically arranged compartments adapted to receive molding sand, of plates adapted to cover the molding sand in the different compartments respectively of said flask-section; slabs arranged over and carrying the different plates respectively, each slab being smaller in dimensions horizontally than the connected plate, and a board arranged above and rigid with said slabs, the relative arrangement of the parts being such that when the plates have entered

the aforesaid compartments from above a suitable distance upon supplying said compartments with molding sand to a suitable height the board is spaced from the top edge 5 of each partition between adjacent compartments.

3. The combination, with a suitably supported horizontally arranged mold-bottom, the lower flask-section embracing the upper 10 portion of said mold-bottom, a double-faced pattern-plate lying in a substantially horizontal position on said flask-section, and the upper flask-section mounted on the pattern-plate, the upper flask-section having vertically arranged compartments adapted to be 15 supplied with molding sand, and the lower flask-section being adapted to be filled with molding sand between the mold-bottom and the pattern-plate, of plates adapted to cover

the molding sand in the different compartments respectively of the upper flask-section; slabs arranged over and carrying the different plates respectively, each slab being smaller in dimensions horizontally than the connected plate, said slabs being tied together, said slabs being compressible independently of the upper flask-section, and said slabs, the upper flask-section the pattern-plate and the lower flask-section being capable of descending together independently of the mold-bottom. 20 25 30

In testimony whereof, I sign the foregoing specification, in the presence of two witnesses.

WILLIAM C. LANG.
